UNITED STATES PATENT OFFICE.

WILLIAM P. FEENEY, OF CHEBOYGAN, MICHIGAN.

FELT CONDITIONER FOR PAPER MACHINES.

Application filed December 17, 1924. Serial No. 756,380.

To all whom it may concern:

Be it known that I, WILLIAM P. FEENEY, a citizen of the United States, and a resident of Cheboygan, in the county of Cheboygan and State of Michigan, have invented certain new and useful Improvements in Felt Conditioners for Paper Machines, of which the following is a full, clear, and exact description.

10 Among the principal objects which the present invention has in view are: to renew the operating condition of the "felts" or carriers employed in paper making machines; to avoid the need for washing the 15 felts with the consequent loss of time, and saving in the expense therefor.

Drawings.

Figure 1 is a side view partly in section 20 of a fragment of a paper making machine having a conditioner mounted thereon, and constructed and arranged in accordance with the present invention, the dotted lines showing the conditioning roll in an elevated or inactive position.

Figure 2 is a front view of the portions 25 of the belt or carrier rolls showing a conditioner in cooperative relation therewith.

Description.

Heretofore, it has been the custom of 30 paper manufacturers to each day wash the felts or carrier belts with which the paper making machine is equipped. This has been done on the supposition that the felts were 35 dirty and therefore in danger of damaging the paper or pulp being carried thereon. This operation has consumed considerable time, care, and consequent expense, which 40 however have been borne on the supposition that it was a necessary evil in the process of manufacture of paper. I have, however, discovered that what the manufacturers 45 have heretofore considered dirt, has in fact been a clogging of the fibers of the woven belt or felt as it is called.

I have discovered that in the process of 50 manufacture the felts in passing between the rollers for pressing the paper, has been so compressed that the woven fibers are mashed so that the interstices become clogged and filled with the fine dust of the paper and thereafter become impervious and unable to pass any moisture contained 55 in the paper. The direct result of this is that the felt becomes discolored in spots or

areas in a manner resembling dirt spots. In the process of washing, the fibers have been opened and the felt has been reconditioned or brought back to the condition in which it 60 originally was.

In accordance with the present invention I recondition the carrier or felt, each part passing it when below and in contact with a roller 8. The roller 8 is placed substantially 65 midway between the carrier rollers 9 and 10, with which the paper making machine is provided. The roller 8 is supported in bearings provided in bracket arms 11 at opposite sides of the paper making machine. The arms 11 are permanently mounted on a shaft 12 which has bearings 70 at the opposite side of the paper making machine and upon the side bars 13 thereof. The roller 8 is provided with a multiplicity 75 of globular knobs extended from the surface of the roller 8 and in suitably juxtaposed and staggered relation.

The purpose of the knobs 14 is to press 80 into the body of the felt or carrier 7 and to sharply bend or spread the fibers at the point where the knobs impinge. When the threads or strands of the felt or carrier are thus opened, any lodgment or flattening of the thread due to the pressure above referred to is eliminated, and the strands will 85 be found stretched to their original rounded shape, so that when the immediate area of the belt affected by any particular knob passes from contact therewith, the threads 90 will be found to be opened, round or in what may be termed a reconditioned condition.

When provided with a reconditioning roller such as the roller 8, the machine will be 95 operated to recondition the felts at any time. This will be done by rocking the shaft 12 to bring the roller 8 in contact with the felt. Pressure is exerted upon the roller to drive the knobs 14 into the body of the felt. To this end a lever 15 is mounted on the 100 shaft 12 and keyed thereto as is best shown in Figure 1 of the drawings. By lifting the lever 15, any desired amount of pressure can be placed upon the roller 8 to stretch and distend the felt between the carrier 105 rolls 9 and 10.

In Figure 1 of the drawings, the broken line indicates the normal position of the felt as stretched between the rolls 9 and 10. The full line indicates the deflected belt or 110 felt. The curved line symbolizing the sectional view of the fabric of the felt shows

the effect of the knob 14 with which it is in contact, the lateral and longitudinal stretch of the fabric being thereby indicated.

The distortion of the threads or strand of 5 the felt laterally is best seen in Figure 2 of the drawings where the knobs 14 are indicated as being buried or pressed into the fabric.

Whenever in the course of operation the 10 felt is found to need reconditioning, this is immediately accomplished by lifting the dog from engagement with the ratchet wheel 17. This permits the roller 8 to fall to the operation position. The pressure is 15 then placed upon the roller by means of the lever 15, the machine continuing to run with the felt 7, passing rapidly under the roller 8 results in kneading the fabric of the felt so that the meshes thereof are 20 thoroughly opened, the strands drawn to their natural rounded shape, and the whole belt is reconditioned or placed in the initial condition thereof. When so reconditioned, the roller 8 is raised by depressing the lever 25 15, and the dog 16 is then thrown to engage the teeth of the ratchet wheel 17 with the result that the roller 8 is maintained idly above and out of engagement with the felt 7 in the position shown by broken lines in 30 Figure 1 of the drawings.

It is obvious that when a reconditioner is constructed and arranged in accordance with the present disclosure, the need for washing the felt is obviated.

35

Claims.

1. A felt reconditioner comprising means for separating the strands of the felt embodying knob-like members adapted to be 40 pressed upon the felt.

2. A felt reconditioner comprising a roller having knob-like projections; means for suspending said roller transverse the felt and in juxtaposed relation thereto; and 45 means for at will forcing said roller upon said felt for pressing the knob-like members into the body of the felt.

3. A felt reconditioner comprising a roller having knob-like projections; means for 50 suspending said roller transverse the felt and in juxtaposed relation thereto; and means for at will forcing said roller upon said felt for pressing the knob-like members into the body of the felt, and means embodying a rocking suspension for said roller, and a power mechanism for rocking said suspension.

WILLIAM P. FEENEY.
